UNITED STATES PATENT OFFICE.

RANSE WRIGHT MILLER, OF DUBLIN, GEORGIA.

DETACHABLE CHOKE PIECE.

Application filed February 4, 1927. Serial No. 165,967.

This invention relates to detachable choke-pieces for attachment to the barrels of shot-guns and the like, and has for its primary object the provision of a device of this character which is extremely simple of construction and may be easily and quickly associated with and locked fast to the barrel of a gun in such manner that there are no movable projecting parts to engage and become fast in hanging limbs, brush or shrubs as the hunter travels.

My inventive-concept contemplates the structural modification of a gun barrel to provide means for associating the choke-piece therewith, the provision of a sleeve of novel construction for connecting the choke-piece to the barrel, and the provision of locking means upon the barrel for engagement with the sleeve to lock the latter in fixed operative position on the barrel, as well as the provision of a choke-piece designed, when associated with the barrel, to concentrate the shot leaving the gun into a smaller area at a distance from the gun than is possible with a cylinder-bore or open-barrel gun.

With these and other objects in view, as will become apparent as the description proceeds, the invention may be said to consist of the novel features of construction, combinations of elements and arrangements of parts hereinafter to be fully described and pointed out in the claims.

A full and complete understanding of the invention may be obtained from a consideration of the following detailed description, taken in connection with the accompanying drawings forming a part of the disclosure, it being understood that while the drawings show a practical form of the invention which has proven satisfactory in use, the latter is not confined to the showing thereof but may be changed and modified so long as such changes and modifications mark no material departure from the salient features of the invention as hereinafter fully described and claimed.

In these drawings:

Figure 1 is a view in side elevation of a portion of a shot-gun barrel, modified, and having operatively associated therewith the sleeve, choke-piece and locking-element, in accordance with my invention;

Fig. 2 is a view in top plan of the structure shown in Fig. 1;

Fig. 3 is a view, in perspective, of a por-

tion of the gun barrel, shown in Fig. 1, with the sleeve and choke-piece removed;

Fig. 4 is a similar view of the associated choke-piece and sleeve, a portion of the sleeve being cut away and portions thereof shown in section, to illustrate the interior construction of the sleeve;

Fig. 5 is a view, in vertical section, taken on line 5—5 of Fig. 3;

Fig. 6 is a similar view, taken on line 6—6 of Fig. 7; and

Fig. 7 is a view in longitudinal central section of the sleeve.

In the particular embodiment of the invention illustrated in the accompanying drawings, the reference-character 1 designates the barrel (only partially shown) of a shot-gun or the like, having a central substantially cylindrical bore 2. In hunting, it is often desirable to direct the travel of the shot issuing from the barrel 1 so that they will be concentrated into a smaller area at a distance from the gun than would be the case if the shot were permitted to travel in the direction which they take when leaving the cylindrical bore 2 of the barrel. At other times, it is desirable to permit the shot to spread over a wide area as they do when issuing from the cylindrical bore. In order that the hunter may be able to quickly adapt the gun either to spread or to concentrate the shot, it is essential that shot-concentrating means be provided which may be accurately and quickly associated with the barrel and locked thereto.

To this end, as shown, the barrel 1 has formed thereon, adjacent its end 3, threads 4 designed to coact with threads 5 on the interior of a hollow cylindrical sleeve 6 to position the latter on the barrel in longitudinal alinement therewith. The threads 4 do not extend entirely around the barrel 1 but are provided only on opposite sides thereof and are spaced or interrupted to produce opposed guideways 7 equal in depth to the height of the threads and slightly wider than the threaded portions 8.

The sleeve 6 is interiorly threaded from end to end and portions of the threads adjacent the inner end thereof are cut away to provide opposed guideways 10 equal in depth to the height of threads 5 and slightly wider than the resulting spaced threaded portions 11.

By reason of this construction, it is possible to aline the threaded portions 8 and 11

with the guideways 10 and 7, respectively, and to slide the sleeve into telescopic relation to the barrel, whereupon a quarter turn of the sleeve with respect to the barrel engages the threads 8 of the barrel with the threads 11 of the sleeve and the guideways 7 and 10 coincide.

The inner end 9 of the sleeve 6 has a portion of the upper side thereof cut away to 10 provide a rectangular opening 12 for the reception of the sight 13 which, in this instance, is carried by a substantially rectangular block 14 fast in the usual position to the barrel 1. The opening 12 is so positioned with respect to the threaded portions 15 11 and guideways 10 and is of such a size that it serves in conjunction with the block 14 to materially aid in the assembling of the sleeve with the barrel in a manner about to 20 be described.

To assemble the sleeve 6 with the barrel 1, the end 9 of the sleeve is telescopically positioned upon the unthreaded end 15 of the barrel and rotated thereon until edge 16, 25 bordering the cut-out 12, is in alignment with side 17 of the sight block 14 which action, by reason of the location of the cut-out with respect to the threaded portions 11 and guideways 10, brings guideways 10 into 30 alignment with the threaded portions 8 on the barrel and threaded portions 11 into alignment with guideways 7, so that the sleeve may be moved inwardly upon the barrel until the edge 18 engages the forward 35 edge 19 of the sight block 14. The sleeve is then rotated in a clockwise direction upon the barrel until edge 20 thereof engages side 21 of the sight block, which action brings the threaded portions 11 into exact register and engagement with the respective threaded 40 portions 8 and the guideways 10 into register with the respective guideways 7.

Preferably and as shown, means for locking the sleeve in operative position on the barrel is provided and, in this instance, comprises a split circular spring band 22 yieldingly engaging and slidable upon the barrel in rear of the sight block 14 and having a pair of forwardly extending locking 45 tongues or keys 23 engageable in the respective guideways 7 to positively prevent relative rotative motion of the sleeve and barrel. As shown, the band 22 has projections 50 24 formed thereon in rear of the keys 23 to 55 serve as handles for use in manipulation of the band to and from locking position. It will be observed that the ends 24' of the spring band 22 are spaced apart a distance approximately equal to the width of the sight block 14 and engage opposite sides thereof when the band is in locking position.

As hereinbefore stated, the sleeve 6 is 60 internally threaded from end to end and the threads 5 at the end 25, remote from the cut-out or opening 12, are uninterrupted

and engage with threads 26 provided on the exterior of a choke-piece 27 to assemble the latter therewith. In order that the inner end 28 of the choke-piece shall snugly abut the end 3 of the barrel when operatively associated therewith, it is desirable to screw it tightly into the sleeve when the latter is locked to the barrel and then more permanently secure it in this position as by means of a set screw 29 threaded from the exterior 75 of the sleeve through the latter and into the choke-piece.

The choke-piece 27, as shown, comprises a cylindrical portion 30 equal in diameter to the barrel 1 and having a bore 31 equal in 80 diameter to the bore 2 and a portion 32 which is also, preferably, cylindrical externally. As best shown in broken lines in Fig. 1, the bore 31 tapers or decreases slightly in diameter toward the forward end 33 of 85 the choke-piece in order that the wall thereof will direct the shot as desired. Obviously, the choke-piece 27 may have any desired degree of internal taper and a plurality of choke-pieces differing as to bore may 90 be selectively associated with the sleeve 6 as the occasion demands. It is to be understood that, after the choke-piece has once been adjusted to the sleeve and to the barrel of a particular gun, the sleeve and choke-piece are then handled as a unit and locking of the sleeve to the barrel in proper position also secures the choke-piece in operative 95 position.

From the foregoing, it will be seen that 100 I have provided a choke-piece assembly which may be quickly and easily associated with and locked to the barrel of a shot-gun or the like, and may be as readily removed therefrom.

What I claim is:

1. In combination, a shot-gun barrel having interrupted threads formed thereon, a sleeve slidable on the barrel and having interrupted threads thereon for engagement 110 with the threads on the barrel, means slidable on the barrel for engagement with the threads on the barrel for locking the barrel and sleeve against relative rotative movement, and a choke-piece carried by the sleeve.

2. In combination, a shot-gun barrel, a sleeve slidable onto the end of the barrel, coacting means on the barrel and sleeve for preventing relative longitudinal movement of the sleeve and barrel, and means coacting 120 with the first-named means to prevent rotative movement of the sleeve relative to the barrel.

3. In combination, a shot-gun barrel, a sleeve slidable onto the end of the barrel, a 125 choke-piece carried by the sleeve, coacting means on the barrel and sleeve for preventing relative longitudinal movement of the sleeve and barrel, and means coacting with the first-named means to prevent rotative 130

movement of the sleeve relative to the barrel.

4. In combination, a shot-gun barrel, a sleeve, coacting threads formed on the barrel and sleeve for removably associating the sleeve in telescopic relation to the barrel, a portion of said threads being cut away to provide a guideway, a locking member slideable on the barrel and including a key for engagement in the guideway to lock the barrel and sleeve against relative longitudinal or rotative movement, and a choke-piece carried by the sleeve.

5. In combination, a shot-gun barrel, a sight block carried by the barrel, interrupted threads on the barrel positioned in predetermined relation to the sight block and providing guideways between groups of threads, a sleeve slideable upon the end of the barrel and having interrupted threads for coaction with the threads on the barrel, said sleeve being formed with means for alinement with an edge of the sight block to bring the threads of the sleeve into register with the guideways to permit sliding of the sleeve onto the barrel to bring the threads of the barrel and sleeve into alinement and rotation of the sleeve on the barrel to cause coaction of said threads, and means movably carried by the barrel and movable into the guideways to lock the sleeve in position on the barrel, and a choke-piece carried by the sleeve.

6. In combination, a shot-gun barrel, a sight block carried by the barrel, interrupted threads on the barrel positioned in predetermined relation to the sight block and pro-

viding guideways between groups of threads, a sleeve slideable upon the end of the barrel and having interrupted threads for coaction with the threads on the barrel, said sleeve being formed with means for alinement with 40 an edge of the sight block to bring the threads of the sleeve into register with the guideways to permit sliding of the sleeve onto the barrel to bring the threads of the barrel and sleeve into alinement and rotation 45 of the sleeve on the barrel to cause coaction of said threads, means movably carried by the barrel and movable into the guideways to lock the sleeve in position on the barrel, and a choke-piece carried by the 50 sleeve.

7. In combination, a shot-gun barrel having interrupted threads formed thereon, a sleeve slideable on the barrel and having interrupted threads therein for engagement 55 with the threads on the barrel, and means slideable on the barrel for engagement with the threads for locking the barrel and sleeve against relative movement.

8. In combination, a shot-gun barrel, a 60 sleeve, coacting threads on the barrel and sleeve for removably associating the sleeve in telescopic relation to the barrel, a portion of said threads being cut away to provide a guideway, and a locking member slideable on the barrel and including a key for engagement in the guideway to lock the barrel and sleeve against relative movement.

In testimony whereof I affix my signature.
RANSE WRIGHT MILLER.
